Application June 13, 1946, Serial No. 676,420

4 Claims. (Cl. 99—391)

1

The present invention relates to broiler apparatus such as is employed in conjunction with inverted-electric element or jet burners, and more particularly to adjustment mechanism for varying the distance between the broiler apparatus and a fixed level at which the burner flames or element is disposed.

In gas as well as in electric ovens there is conventionally provided a broiler chamber which is provided with one or more heat elements or jet burners disposed and designed so as to throw heat downwardly against food so as to prepare said food by broiling or top surface heating. In the case of gas jet burners, the flames are directed downwardly and the distance between their lower-most extremity of effective heat and the horizontal location of the food constitutes a critical factor in determining the period of time required for the consummation of the cooking operation as well as the intensity or penetration effect produced upon the food during the process.

Various classes of devices have been heretofore used and proposed, possessed of but coarse degrees of adjustment or having otherwise unsatisfactory results. Frequently the distance between consecutive, even closely spaced wall support brackets is too great to afford close adjustment characteristics such as are considered of prime importance in achieving culinary perfection. This insufficiency throws an unnecessary burden upon the chef and requires closer attention than would otherwise be requisite.

Where adjustable mechanism with fine degrees of variation has been proposed heretofore, costly and sometimes intricately moving parts have thereby been subjected to the intense heat and oxidation which is incident to the operation of broiling, with the consequent effects that these parts have been difficult to clean or have presented difficult tasks towards the attainment of a cleanliness standard in keeping with food preparation.

Accordingly in overcoming the difficulties and adversities which beset previous practices and attempts at achieving a satisfactory solution of this problem, it is proposed herewith to utilize an adjustable broiler mechanism having infinite variations of adjustment and which nevertheless partakes of simple and accessible component elements so as to be readily maintainable in cleanliness under all conditions of operation.

Briefly stated, the principal object of the present invention is to provide a broiler mechanism which is adaptable to conventional space and facility conditions of oven apparatus which will lend itself to infinite horizontal level adjustment

so as to accommodate the full range of cooking requirements, and one which may be manufactured economically of low cost materials and which will lend itself to facile maintenance in sound operating condition and dietary cleanliness.

For a more comprehensive understanding of the present invention reference will now be had to the accompanying drawings and to the following detailed specification in which like reference characters designate corresponding parts throughout and in which:

Fig. 1 is a front elevational view of a representative oven chamber and frontal door with portions broken away to reveal the posterior construction and having incorporated therein one embodiment of the present invention;

Fig. 2 is a plan view of the broiler apparatus featured in the illustration of Fig. 1 with a portion of the surrounding oven structure broken away;

Fig. 3 is a detailed perspective view of one of the three welded supporting brackets carried by the broiler platform and designed to rest upon the spiral trackways of the broiler pan;

Fig. 4 is a plan view of a modified embodiment of broiler platform and adjustment apparatus;

Fig. 5 is a side elevational view of the apparatus featured in Fig. 4 with a portion of the bottom or drip pan broken away;

Fig. 6 is a perspective view of a tri-segmental supporting structure and trackway elements;

Fig. 7 is a fragmentary sectional detail view taken approximately on line 7—7 of Fig. 4; and

Fig. 8 is a fragmentary detail view taken approximately on line 8—8 of Fig. 4.

In the embodiment of the present invention featured in Figs. 1 to 3, inclusive, a conventional gas jet broiler burner is designated 11. The broiler chamber is defined by side and back walls and by the front panel 12 which has a rectangular opening 13 that is covered or closed by any conventional type of closure door 14 that may be pivoted or removably fastened after well-known manners of construction. The door 14 is customarily manipulated by means of a strap type handle 15 and upon being withdrawn or swung out of position exposes the substantially rectangular broiling oven chamber.

The distance downwardly that the gas flames 16 extend or through which they may be effectively projected against the food under preparation can of course be regulated by means of any well known type of gas cock adjustment or in accordance with more modern trends by means of a thermostatically controlled gas adjustment.

55 Where this adjustment is automatically controlled

for the sake of regulating oven temperatures of the baking oven chamber 17 above the broiler, the raising of the mean temperature within the oven effects an automatic regulation upon the gas flame 16 so as to require secondary adjustments following a period of operation.

In order to obviate such secondary adjustments the oven door 18 may be left open so as to lower the baking oven temperature, but preferably the initial adjustment may be protracted until a sufficient period of time has elapsed so as to establish a basic oven temperature whereby to avoid having to make this secondary oven regulation.

Thereafter the flame adjustment on the burner 11 will remain nearly constant and also as a result of such preparatory practice the broiler chamber is brought up to an even and efficient heat level preparatory to the broiling operation.

In order to accommodate more practically the provisions of the instant improvement the broiling chamber 19 is fitted with defining side or support walls 21 and 22 and with a back wall 23, all preferably of sheet metal secured at various points as at 24 by spacers and securement bolts to principal supporting wall sections. The side supporting walls 21 and 22 are provided with trackways or ledges 25 upon which is adapted to rest the beaded edge 26 which defines the upper peripheral extremity of a broiler pan 27.

The cylindrical side wall 28 of the broiler pan 27 is indented preferably at three peripheral equally spaced positions so as to provide inwardly jutting trackways 29, 30 and 31. These trackways are all similar in shape, proportion and disposition in their respective segments of the pan 27 so that the inner supporting ledges 32 afforded by the indentations of said trackways provide equilateral support to the three equiangularly spaced engagement brackets 33 carried by the broiler platform 34.

Each bracket 33, as best indicated in Fig. 3, consists of a wall segment secured as by spot-welding to the apron flange 35 of the platform 34, and a substantially U-shaped formation 36 bent at right angles to the wall segment for resting upon one of the trackway ledges 32. By rotating the platform 34 throughout substantially 120°, the brackets 33 may be made to rise or descend, depending upon the direction of rotation, and since the brackets are equally spaced in correspondence with the equal spacing of the trackways 29 to 31, horizontal level of the platform 34 is maintained.

The platform 34 may be sloped inwardly or it may have concentric undulations in order to facilitate the collection of broiling juices in minimum areas so as to be dischargeable through ornamentally arranged openings 37 situated in valley portions of said undulations.

The adjustment of the platform 34 is preferably effected in advance so that handling thereafter under heated conditions may be avoided. But slight experience in this manipulation is deemed adequate to suffice in the anticipation of predetermined adjustment, although by means of the infinite variations afforded, this adjustment may be accurately made by measuring or by observing the disposition with respect to side markings (not shown) in the broiler pan.

It is to be observed that the broiler pan may be very easily dismantled and that no sharp projections or inaccessible areas result from the provision of the described adjusting mechanism. The undulations of the platform 34 are easily accessible as are surfaces of typical culinary de-

vices and lend themselves to sterilizing and cleansing in keeping with high standards of sanitation.

Modification

5 In the modification illustrated in Figs. 4 to 8, inclusive, a similar arrangement of parts is contemplated, except that the broiler pan in this modification need be but a relatively shallow instrumentality designated 51, Figs. 4 and 5 with-
10 in which there is adapted to reside the annular footing ring 52 of a wire trackway assembly. At three equally spaced points 53, Fig. 6, there are secured as by welding, the vertical supporting posts 54 which may be of the same wire stock as that of the footing ring 52, designated 55, 56 and 57. One or more of said elements 55 to 57 is studded on its upper surface or surfaces with the indentations or notches 58 provided for the purpose of preventing inadvertent slippage of the hooked portions 66 after effecting the broiler platform adjustment, as will be seen later.

15 Between one of the track segments such as for example 57 and its related vertical supporting post 54, there is formed a thumb loop or handle 59, Fig. 6, whereby the entire assembly may be rotated within its seating pan 51, and whereby also there may be engaged the trackway assembly relative to effecting movement of the broiler unit 61 for adjustment purposes as will now be de-
20 scribed.

25 The broiler unit may be constructed of an assembly of radially extending wire rod sections, in the illustrated example, six in number, three of which are longer and designated 62 relative to the intermediate three which are shorter and designated 63. At their common intersection center these rods may be anchored as by spot-welding to a center disc 64 while to one of the rods 62 there is secured also preferably by welding a manual engagement loop 65, Figs. 5 and 7, for achieving regulation in cooperation with the aforementioned frame loop 59.

30 The longer rods 63 each are provided with undeturned extremities or hooked portions 66, Fig. 8, one of which is slightly shorter, as designated at 67, Fig. 7, to facilitate springing over its associated track 57, while the remaining ones of which are longer as at 68, Fig. 8, to achieve relative securement with its related track segments 55. The shorter radial rods 63 extend outwardly far enough only to support the several involute surface forming spirals 69 which compositely constitute a platform comparable with the undulate surface of the platform 34, described above.

35 The several trackways 55, 56, and 57 are butt-welded to the vertical supporting posts 54 of the next contiguous segments as best indicated at 71 so as to provide rigidity for supporting the platform assembly 61. By rotating the platform 60 throughout substantially 120° surface adjustment according to infinitely variable levels may be approximated after the manner described in the first described embodiment above, and in order to assure that each adjustment is maintained, the 65 encircling loops 66 of the spider rods 63 may be permitted to reside within the indentations 58 already mentioned.

70 In order to dismantle this embodiment of the invention it is but necessary to spring the shortest one 67 of the three hooked portions 67-63, Fig. 7, over its related track wire 57, whereupon the remaining hooked portions 68 may be simply unhooked and the platform withdrawn.

75 Since the entire assembly is constituted of round wire stock, contacting surfaces are mini-

mum and accessibility for cleansing is afforded to an appreciably greater extent than in the cases of heretofore known practice.

While the present invention has been illustrated and described with reference to specific contemplations of embodiment it is to be understood, nevertheless, that numerous variations and modifications may be invoked without departing from the essential spirit or scope thereof. It is intended accordingly not to be limited by any of the detailed illustrations in the accompanying drawings nor by the particular language employed in the foregoing description, except as indicated in the hereunto appended claims.

The invention claimed is:

1. In combination with a broiler burner, a principal supporting apparatus comprising a circular grid assembled of a series of radial rods certain ones of which are provided with extreme trackway engaging hooks, a system of involute grid elements in planar alignment secured to said radial rods in spaced relation each to each, a framework for supporting said apparatus comprising a footing ring, a series of wire trackways including vertical members welded to said footing ring, a drip pan within which said footing ring is adapted to rest, and manipulation means associated with said framework and with said platform whereby said platform may be rotated with respect to said framework and said engaging hooks made to ascend or descend upon their said trackways for producing variations in elevation adjustment.

2. In combination, a grid for boilers formed of a plurality of radial rods arranged in a plane, certain ones of which are provided at their outer extremities with trackway engaging means, a series of involute grid elements secured to said radial rods in spaced relation to each other, a framework for supporting said platform comprising a series of wire trackways, vertical members for supporting said trackways, manipulation means associated with said framework and with said platform whereby said platform may be rotated with respect to said framework to ascend and descend upon their said trackways for effecting variations in elevation adjustment.

3. In a broiler apparatus, a circular grid fabrication of wire having three equiangularly spaced radial members, extremities on said members doubled over to form open hooks, a supporting framework of wire comprising a footing ring and three complementary spiral trackways at least one of which is provided with surface notchings, said hook formations adapted to be sprung each over one of said trackways, for riding the length of said trackways concurrently and means for rotating said grid with respect to said framework whereby said hooks are disposed at corresponding levels on respective ones of said trackways.

4. In a circular grid for food preparation, a supporting spider comprising a plurality of radially extending rods arranged in planar alignment, a series of circumferentially spaced involute rods supported on said radially extending rods and welded thereto at various contacting intersections therewith, certain of said radially extending rods being formed at their outward extremities with downwardly bent hook portions, and a plurality of circumferential supports engageable by said hook portions and having, concentric with said circular grid, rod trackways of varying elevation whereby to afford through rotational placement of said grid elevational adjustment thereto.
